Primary Examiner — Marcus Jackson*(74) Attorney, Agent, or Firm* — Dicke, Billig & Czaja PLLC**CLAIM**

The ornamental design for a LED light bulb, as shown and described herein.

DESCRIPTION

FIG. 1 is a front, right perspective view of a LED light bulb, according to one example of the present disclosure, with elements in dashed lines forming no part of the claimed design;

FIG. 2 is a bottom plan view of the light bulb of FIG. 1;
 FIG. 3 is a top plan view of the light bulb of FIG. 1;
 FIG. 4 is a front side view of the light bulb of FIG. 1, with a rear side view being a mirror image of the front side view;
 FIG. 5 is a left side view of the light bulb of FIG. 1; and,
 FIG. 6 is a right side view of the light bulb of FIG. 1.
